UNITED STATES PATENT OFFICE.

OTIS F. PRESBREY, OF BROOKLYN, NEW YORK.

ROTARY MOTOR.

Application filed June 10, 1920, Serial No. 387,950. Renewed August 5, 1925.

To all whom it may concern:

Be it known that I, OTIS F. PRESBREY, a citizen of the United States, and resident of Brooklyn, in the county of Kings and State of New York, have invented certain new and useful Improvements in Rotary Motors, of which the following is a specification.

The invention relates to a rotary motor capable of varied uses and comprising, in a special construction and arrangement of parts, a rotary casing from which power may be transmitted, a stationary shaft extending through said casing and arranged eccentrically thereto, two parallel sets of cylinders rotatably mounted on said shaft, one of said sets being high pressure cylinders and the other low pressure cylinders, and pistons mounted in the respective cylinders and adapted thereto and being free to reciprocate, not being fastened either to the stationary shaft or to the outer case ring. The pistons are alternately provided at their outer ends with shoes and rollers to engage the inner surface of the ring or band of the exterior casing, and the cylinders, within which said pistons move, receive the motive fluid at appropriate periods at their inner ends. I preferably employ within the motor twelve cylinders, six being high pressure cylinders and six low pressure cylinders, and preferably these two sets of cylinders are formed in integral side by side castings suitably mounted to rotate on said shaft and confined, with their pistons, wholly within the exterior casing, which will be oil tight and contain at all times a suitable quantity of oil for lubrication purposes. The cylinders are radially disposed and preferably spaced sixty degrees apart, and said cylinders are entirely open at their outer ends so as to permit the pistons to readily perform their necessary strokes. In the operation of my motor, the cylinder assemblies are eccentric to the center of the main casing, and preferably the distance between the axial center of the cylinder assemblies and the axial center of the rotary casing is equal to about one-half of the stroke of the pistons in said cylinders, and hence during the operation of the engine the pistons

successively engage, with driving effect, the inner surface of the case ring and effect the rotation of the same. In the construction and operation of the motor I provide suitable ports so disposed that the fluid pressure is applied to the successive pistons when they are at their maximum inner center or inner position within their respective cylinders and the arc prescribed by the cylinder and the arc prescribed by the case ring are closest together. The distance between these two arcs increases from this point and the length of the piston stroke is governed by this varying distance. The outer center of the piston stroke is one hundred and eighty degrees from its inner center, at which point the distance between the aforesaid arcs is the greatest.

I present my invention herein as embodied in a rotary motor adapted to operate on steam, but I do not confine the invention to the employment of steam as the motive power, since the broader features of my invention may be embodied in an engine adapted to be operated by gases, other than steam, or liquids under pressure, it being necessary, under such circumstances, to properly arrange the inlet and exhaust and provide, in the case of explosive gases, for proper ignition. When the engine is arranged as an internal combustion engine, mechanical means will be provided to cause the pistons to travel outwardly on their suction strokes.

The invention resides in the novel features, structure, arrangement and combinations of parts hereinafter described and claimed and will be fully understood from the detailed specification hereinafter presented, with reference to the accompanying drawings, in which:

Fig. 1 is a side elevation of a rotary motor constructed in accordance with and embodying my invention;

Fig. 2 is a vertical section through the same, taken on the dotted line 2—2 of Fig. 5;

Fig. 3 is a detailed vertical section through the stationary shaft and particularly of that portion thereof on which the casting for the high pressure cylinders is mounted, a portion of said casting being shown in sec-

tion, and Fig. 3 being presented more particularly for illustrating the disposition of the ports within said shaft and the passages leading therefrom to the respective high pressure cylinders;

Fig. 4 is a corresponding view through the shaft and a portion of the casting in which the low pressure cylinders are formed;

Fig. 5 is a vertical section, taken through the engine, on the dotted line 5—5 of Fig. 2, but illustrating the cylinder castings as having been so turned into parallelism that the high pressure cylinders and low pressure cylinders stand side by side instead of in the staggered order shown in Fig. 2, this disposition of the cylinder castings in Fig. 5 being in the interest of better illustration.

In the drawings, 10 designates a stationary axle shaft, 11 a stationary eccentric shaft, 12 the ring or cylinder of the main casing, 13 a closing plate for one side of said casing, 14 a substantially corresponding closing plate for the other side of said casing, 15 a closing cap for the central portion of one side of the main casing, and 16 a retaining ring or plate at the opposite side of said casing. The main casing as a whole is mounted to rotate around the axial center of the axle 10, said casing at one side being mounted on ball bearings 17 and at the other side on ball bearings 18. The ball bearings 17 are held between race-ways 19, 20, and the side 14 is recessed, as at 21, to receive said race-ways, the inner race-way 19 being on a cylindrical section 22 of the axle 10 and the race-way 20 being exterior thereto and closely fitting the outer portions of the recess 21. The race-ways 19, 20 are confined at their outer ends by a nut 23 and the aforesaid ring plate 16, which, by means of screws 24, is fastened to the side 14 of the main casing. The inner edge of the race-way 19 abuts against a shoulder 25 provided on the axle 10, and the inner edge of the race-way 20 abuts against an annular flange 26 which matches the peripheral edges of the ring 27 affording said shoulder 25. At the outer end of the eccentrically disposed shaft 11 there is formed a reduced section 28 upon which is mounted an eccentric 29, and upon this eccentric, by means of the aforesaid ball-bearings 18, is mounted the right hand side, looking at Fig. 5, of the main casing of the engine, the ball-bearings 18 being disposed between inner and outer race-ways 30, 31, respectively, and the race-way 30 being set in a recess in the periphery of the eccentric 29 and the race-way 31 in a recess formed in the side 13 of the casing. The race-way 31 is kept in its position by the engagement of the inner edges of the closing cap 15 therewith, and the race-way 30 is held in place in its recess by means of a retaining plate 32 and nut 33, as will be readily understood on reference to Fig. 5.

On the removal of the cap 15, nut 33 and plate 32, the race-ways 30, 31 become exposed and may be removed. By means of the eccentric 29, the sides 13, 14 of the main casing become correspondingly mounted on the axial center of the shaft 10, and hence the casing as a whole has a uniform rotary motion on the line of a circle about said center. The sides 13, 14 are secured to the opposite edges of the ring 12 by means of screws 34.

35 designates the high pressure cylinders, 36 the pistons therefor, 37 the low pressure cylinders, and 38 the pistons therefor. The high pressure cylinders 35 are preferably formed in an integral hub casting 39, and the low pressure cylinders 37 are preferably correspondingly formed in an integral casting 40, and both of these castings are mounted side by side upon the eccentric shaft 11, as shown in Fig. 5.

The integral casting 40 for the low pressure cylinders has a hub portion and the series of cylinders 37 formed therein and said cylinders are open at their outer ends and at their inner ends have inlet ports 41, as shown in Fig. 4, for the admission of steam at the proper periods to act against the pistons 38. The cylinder chambers are formed radially in the casting 40, as shown in Fig. 2, and, in the construction presented, I make use of six of the cylinders 37. These cylinders are integral with the hub portion of the casting 40 and at adjacent sides are connected together by webs 42, as shown in Fig. 2. The casting 40 is mounted on a sleeve 43 located on the inner or left hand end of the eccentrically disposed shaft 11, as shown in Fig. 5. The sleeve 43 at its inner end abuts against a race-way 44 which faces an annular race-way 45 set in a recess in the left hand edge of the hub portion of the casting 40, and between the race-ways 44, 45 are the ball-bearings 46. At its outer or right hand side the hub portion of the casting 40 is recessed, as at 47, to receive a portion of an annular race-way 48 which encompasses a cooperating race-way 49 set up against a shoulder 50 formed on the sleeve 43, and between the race-ways 48, 49 are ball-bearings 51. The block of low pressure cylinders 37 rotates around the sleeve 43 and upon the ball-bearings 46, 51, as will readily be understood on reference to Fig. 5.

The casting 39 for the low pressure cylinders 35 corresponds substantially, except as to proportions, with the casting 40 for the series of low pressure cylinders 37. The cylinder chambers of the high pressure cylinders 35 are less in diameter than the cylinder chambers of the low pressure cylinders 37, and said cylinders 35 have open outer ends and at their inner ends communicate with or have ports 52 for the admission of steam to said cylinders. The casting 39

for the high pressure cylinders is mounted on a reduced portion 53 of the sleeve 43 which extends along the shaft 11 within the hubs of both sets of cylinders, as shown in Fig. 5, and the inner or left hand side, looking at Fig. 5, of the casting 39 is recessed to receive the right hand portions of the race-ways 48, 49, while at the right hand side of the casting 39 the hub portion thereof is recessed, as at 54, to receive the race-ways 55, 56, between which are ball-bearings 57. The casting 39 becomes thus mounted upon the ball-bearings 51, 57, and, as shown in Fig. 5, the race-way 56 abuts against the right hand end of the sleeve 43. The inner race-way 49 abuts against a shoulder 50 of the sleeve 43, and the inner left hand edge of the casting 39 is adjacent to a shoulder 58 on said sleeve 43, while the inner race-way 57 abuts against the end of the sleeve 43, said end serving as a shoulder; the castings 39, 40 are thus kept from undue binding action against each other, and said castings may be further separated by a thin washer 59 of any suitable material, said washer serving as a thrust washer and being, if preferred, of bronze.

The pistons 36, 38 substantially correspond with each other, except as to diameter, although I preferably taper the inner ends of the low pressure pistons 38, as shown in Figs. 2 and 5, and leave the inner ends of the high pressure pistons 36 either flat or make them slightly concave, as indicated by the dotted lines in Fig. 5. There being six of the high pressure cylinders 35, there will be six pistons 36 therefor, and each alternate piston 36 will have, at its outer end, a roller 60 to engage the inner surface of the case ring 12, while the other pistons 36 will carry shoes 61 to engage said inner surface of the case ring 12, said shoes having convex outer faces and a shank portion 62 which passes between the outer bifurcated ends of the cylinders and is bored to swivel upon a sleeve 63 held with the shank portion upon a pin 64 extending through the end of the piston and bushing 68. The low pressure pistons 38 are alternately provided with outer end rollers 65 and shoes 66, corresponding with the rollers 60 and shoes 61 of the high pressure pistons 36, and hence not requiring any specific description. The rollers 60, 65 are mounted on pins 67 which extend through the bifurcated outer ends of the alternate pistons 36, 38. The shoes 66 have the same mounting as the shoes 61 and, as shown in Fig. 5, the shoes 66 are pivotally mounted on bushings 68, held within the outer ends of the pistons 38 by means of pins 69.

Passages and ports for steam.

The intake port or passage for steam extends through the shaft 10 and into the eccentric shaft 11 and is numbered 70, and said intake is shown by dotted lines in Fig. 5 and, as illustrated, breaks through the eccentric shaft 11 at the opening 71 (Fig. 3). The delivery end 71 of the intake 70 is in line with a segmental slot 72 formed in the sleeve 53 on which the hub or casting for high pressure cylinders is mounted, and the steam from the outlet of the intake 70 will pass into said slot 72 and therefrom into any of the ports 52 of the cylinders 35 which may pass into line with it. In Fig. 3 we show one port 52 as traveling toward the slot 72, another port 52 in full engagement with and traveling along said slot, and a third port 52 as receding from the slot 52 and passing upon a solid portion of the sleeve 53. The inlet for live steam is, therefore, through the passage or intake 70, thence from the outlet 71 thereof into the slot 72, and thence into such cylinders 35 as may be in register or partly in register with said slot 72. The steam primarily utilized in the high pressure cylinders 35 exhausts for further use into the low pressure cylinders 37, and in Fig. 3 it may be seen that the sleeve 53 is formed, opposite to the slot 72, with a somewhat longer slot 73, and that the ports 52 of the high pressure cylinders pass into register with said slot 73, whose purpose is to afford a passage for the exhaust from the high pressure cylinders, as said cylinders become aligned with said slot. The exhaust steam entering the slot 73 will exhaust into or enter ports or passages 74, 75, respectively, (Figs. 3 and 5). The passage 74 is an elongated hole or passage cut through the eccentric shaft 11 on a transversely slanting line and has its outlet at 76, as represented in Figs. 4 and 5.

The passage or port 75 extends along practically parallel with the port or passage 74, and finally opens into a slot 77 formed in the sleeve 43 at a point around which the low pressure cylinders travel. The passage or port 74 at its outlet 76 also discharges into the slot 77, and hence the high pressure steam may exhaust into the low pressure cylinders from both the ports 74 and 75 as said cylinders carry their ports 41 along said slot 77. I preferably use both ports 74, 75 so as to increase the port area or capacity to carry the steam from the high pressure side to the low pressure side of the motor.

The exhaust from the low pressure cylinders is from said cylinders as their ports 41 are carried along and register with a segmental slot 78 in the sleeve 43, as shown at the right hand side of Fig. 4, and thence or from said slot 78 into and through a passage or port 79 extending from within the eccentric shaft 11 through the axle or shaft 10, as indicated by dotted lines in Fig. 5. I also provide in the axle 10 a vent passage 130

80, as shown by dotted lines in Fig. 5, extending from the interior chamber of the motor for venting the same.

Operation.

- 5 A suitable quantity of oil may be introduced into the chamber of the main casing of the motor for lubrication purposes, according to well understood principles. Lubrication of the cylinders and pistons may be provided for by allowing a quantity of oil to drip into the intake steam, and excess oil after lubrication of the pistons and cylinders, is allowed to accumulate in the 10 main casing, where it in turn lubricates the shoes 61, 66, rollers 60, 65 and case-ring 12. Any leakage of steam from the cylinders or steam generated by water condensed from steam-leakage, may exhaust through 15 the passage 80, leaving the oil in the main casing and relieving the chamber of the casing from any pressure which might otherwise be produced therein.
- The cylinder casings 39, 40 are both free 20 to rotate on the eccentric shaft 11 and sleeves 43, 53, which may be considered as parts of said shaft, and the casing rotates on the ball-bearings 17, 18.
- Steam admitted through the intake passage 70 will pass from the outlet port 71 of said passage into the segmental slot or elongated port 72 formed in the sleeve 53 and located in the upper left hand portion, looking at Fig. 3, thereof and in the path 25 of the ports 52 formed in the inner ends of the high pressure cylinders 35. As the cylinder block or casting 39 rotates, the ports 52 thereof are carried along the elongated port 72 and receive steam therefrom.
- 30 Steam entering the ports 52 of the high pressure cylinders, drives the pistons 36 therein outwardly and this causes the shoes 61 and rollers 60 of said pistons then active to firmly engage the inner surface of the ring or band 12 as may be seen on reference to the upper left hand portion of Fig. 2. The engagement of said shoes 61 with the ring 12 effects the rotation of the main casing, and during this rotation the said rollers 35 slip or roll on the inner surface of the ring 12, so that the pistons under steam pressure but not actively driving the main casing may not retard the rotation of the same. As the cylinders 35 pass beyond the 40 elongated port 72, or downwardly counter-clockwise therefrom, looking at Fig. 3, the intake steam becomes cut off therefrom, and as said cylinders 35 reach the segmental slot or elongated port 73 the steam confined in 45 said cylinders exhausts into said port 73 and thence into the passages 74, 75 and passes thence into the segmental slot or elongated port 77 in the sleeve 43, whence said steam enters, through ports 41, the low pressure 50 cylinders 37 as said cylinders travel along

said port 77. The steam which enters the successive cylinders 37 passing along the port 77 is effective to drive the pistons 38 therein outwardly to carry their shoes 66 and rollers 65 outwardly against the inner 70 surface of the case-ring 12, with the result that said shoes will act to impart rotary motion to the main casing, in aid of the shoes 61 of the high pressure pistons, the rollers 65 rolling on said surface. After the steam 75 which enters the low pressure cylinders has performed its duty, said steam will exhaust through the elongated slot or port 78 and passage 79.

The high pressure cylinders and low pressure cylinders may assume a staggered order, transversely considered, as shown in Fig. 2, and in the operation of the engine both a high pressure piston and a low pressure piston are always acting with efficiency 80 to drive the case-ring 12, as will be understood on reference to the upper left hand portions of Figs. 2, 3 and 4. It will also be understood on reference to Figs. 2, 3 and 4, that the steam is admitted to the successive 90 cylinders when the pistons therein are at their maximum inner center and when the are prescribed by said respective cylinders and that prescribed by the case-ring 12 are 95 closest together, and also that from this admission point the distance between said two arcs gradually increases, the stroke of the pistons being governed accordingly. The outer center of the piston-stroke is one hundred and eighty degrees from its inner center, and at this point, or outer center, the distance between the aforesaid arcs is the 100 greatest.

The rotation of the main casing of the motor is utilized as a source of power which 105 may be transmitted therefrom in several ways, in accordance with the work to be performed. For illustration, a transmission belt may be applied directly on the case-ring 12 to be driven therefrom, thus converting said ring into a pulley. A conveyor belt may also be applied on the case-ring 12 and driven therefrom. The ring 12 may also obviously be utilized as a pulley for a 110 chain drive.

If the motor should be used on a flying machine, the cap 15 would be removed from the casing and the shaft of the propeller of such machine would be fastened to said casing in the place of said cap.

The invention may be applied to use for driving vehicles, in which use two of the motors would be employed and serve as hubs for the wheels, the motors being mounted on the dead axle as indicated by the dotted 125 lines at the left hand side of Fig. 5.

The invention presents many advantages which will be understood without elaborate detailed explanation, and among these may be mentioned that of securing the most di- 130

rect and economical conversion of pressure into power, the greatest starting torque, the lack of necessity for a skilled operator, smoothness of operation, small cost of production, and ease of assembly and repairs.

5 The engine will operate in any position. When it is desired to reverse the engine, the steam is admitted through the exhaust passage to the low pressure cylinders first.

10 I have described my motor in a form designed for operation by steam, but do not wish to confine my invention to its construction for operation by steam, since I am aware that with suitable modification my invention 15 may be utilized in motors to be operated by gases other than steam and also by fluids at present used in motors. Nor do I confine my invention to the details of form and construction hereinbefore described adapting the motor to be driven by steam, since in the illustration of my invention presented herein I have sought to define the preferred embodiment thereof, without intending to indicate that my invention can 20 not be carried out in other forms and arrangements of mechanical detail.

In case it should be desired to employ a liquid, as oil, for the motive fluid, I would employ several corresponding sets of the 30 cylinders and pistons and omit low pressure cylinders.

I prefer to form the independently rotatable cylinder-blocks 39, 40 each in one 35 integral casting, but it is to be understood that these blocks or cylinder-assemblies may be built up in several pieces if so desired.

What I claim as my invention and desire to secure by Letters-Patent, is:

1. A rotary motor of the type described comprising a rotary closed casing from which power is to be transmitted and having sides and an encompassing ring or band secured thereto and having a uniform circular inner surface, a fixed axle on which one 40 of said sides is concentrically mounted, an eccentric shaft connected at one end with said fixed axle and eccentrically traversing said casing, an eccentric on the other end of said eccentric shaft on which the other side 45 of said casing is mounted and which cooperates with said fixed axle in concentrically mounting said casing, a sleeve on said shaft and constituting a portion thereof and having a larger diameter at its inner portion than at its outer portion so as to receive and permit the convenient removal of the several parts to be mounted on said shaft, a removable cap secured to one side of said casing at 50 said eccentric and permitting on its removal the removal of said eccentric, a plurality of side-by-side cylinder-blocks concentrically mounted on said diameters of said sleeve and each having a series of radially disposed cylinders provided with ports at their inner ends, the cylinders of one block being in 55 staggered relation to the cylinders of the other block, independent pistons slidable within said cylinders and exposed at their outer ends and adapted to engage the inner circular surface of said band and rotate said casing, ports leading to the ports of said cylinders which may be traveling along those portions of their movements when the arc prescribed by said cylinders and that prescribed by said casing are approximately 60 closest together and gradually diverging, and ports to register with the ports of said cylinders to permit exhaust therefrom as said cylinders travel beyond the active zones for their respective pistons.
3. A rotary motor of the type described comprising a rotary casing having opposite sides and an encompassing ring or band presenting a uniform circular surface and from which power is to be transmitted, bearing members on which the opposite sides of said casing are mounted, a plurality of side-by-side rotary cylinder-assemblies each having a series of radially disposed cylinders and independent pistons slidable therein and adapted at their outer ends to engage said circular surface of said band and rotate said casing, and inlet and exhaust ports for said cylinders, said casing and said cylinder-assemblies being eccentrically disposed with 65 respect to each other, and said inlet ports

scribed by said cylinders and that prescribed by said casing are approximately closest together and gradually diverging and an outlet to register with the ports of said cylinders to permit exhaust therefrom as said cylinders travel beyond the active zones for their pistons.

2. A rotary motor of the type described comprising a rotary closed casing from which power is to be transmitted and having 70 sides and an encompassing ring or band secured thereto and having a uniform circular inner surface, a fixed axle on which one of said sides is concentrically mounted, an eccentric shaft connected at one end with 75 said fixed axle and eccentrically traversing said casing, an eccentric on the other end of said eccentric shaft on which the other side of said casing is mounted and which cooperates with said fixed axle in concentrically mounting said casing, a sleeve on said shaft and constituting a portion thereof and having a larger diameter at its inner portion than at its outer portion so as to receive and 80 permit the convenient removal of the several parts to be mounted on said shaft, a removable cap secured to one side of said casing at 85 said eccentric and permitting on its removal the removal of said eccentric, a plurality of side-by-side cylinder-blocks concentrically mounted on said diameters of said sleeve and each having a series of radially disposed cylinders provided with ports at their inner ends, the cylinders of one block being in 90 staggered relation to the cylinders of the other block, independent pistons slidable within said cylinders and exposed at their outer ends and adapted to engage the inner circular surface of said band and rotate said casing, ports leading to the ports of said 95 cylinders which may be traveling along those portions of their movements when the arc prescribed by said cylinders and that prescribed by said casing are approximately closest together and gradually diverging, and ports to register with the ports of said cylinders to permit exhaust therefrom as 100 said cylinders travel beyond the active zones for their respective pistons.

3. A rotary motor of the type described comprising a rotary casing having opposite sides and an encompassing ring or band presenting a uniform circular surface and from which power is to be transmitted, bearing members on which the opposite sides of said casing are mounted, a plurality of side-by-side rotary cylinder-assemblies each having a series of radially disposed cylinders and independent pistons slidable therein and adapted at their outer ends to engage said circular surface of said band and rotate said casing, and inlet and exhaust ports for said cylinders, said casing and said cylinder-assemblies being eccentrically disposed with 110 respect to each other, and said inlet ports

being arranged to admit the motive fluid to the cylinders as they travel along that portion of their movement when the arc prescribed by said cylinders and that prescribed by said casing are in near relation and gradually diverging.

4. A rotary motor of the type described comprising a rotary casing having opposite sides and an encompassing ring or band presenting a uniform circular surface and from which power is to be transmitted, bearing members on which the opposite sides of said casing are mounted, a plurality of side-by-side rotary cylinder-assemblies each having a series of radially disposed cylinders and independent pistons slideable therein and adapted at their outer ends to engage said circular surface of said band and rotate said casing, and inlet and exhaust ports for said cylinders, said casing and said cylinder-assemblies being eccentrically disposed with respect to each other, and said inlet ports being arranged to admit the motive fluid to the cylinders as they travel along that portion of their movement when the arc prescribed by said cylinders and that prescribed by said casing are in near relation and gradually diverging, and said pistons of each series being alternately provided at their outer ends with pivoted shoes and rollers to engage said casing.

5. A rotary motor of the type described comprising a rotary casing having opposite sides and an encompassing ring or band presenting a uniform circular surface and from which power is to be transmitted, bearing members on which the opposite sides of said casing are mounted, a plurality of side-by-side rotary cylinder-assemblies each having a series of radially disposed cylinders and independent pistons slideable within said cylinders adapted at their outer ends to engage said circular surface of said band and rotate said casing, the cylinders of one assembly being high pressure cylinders and of the other assembly low pressure cylinders and said casing and said cylinder-assemblies being eccentrically disposed with relation to each other, an intake for motive fluid leading to said high pressure cylinders which may be traveling along those portions of their movement when the arc prescribed by said high pressure cylinders and that prescribed by said casing are in near relation and gradually diverging, an exhaust extending from said high pressure cylinders as said cylinders successively travel beyond the active zone for their respective pistons and leading to said low pressure cylinders which may be traveling along those portions of their movement when the arc prescribed by said low pressure cylinders and that prescribed by said casing are near together and gradually diverging, and an exhaust from said low pressure cylinders as said cylinders travel beyond the active zone for their pistons.

travel beyond the active zone for their pistons.

6. A rotary motor of the type described comprising a concentrically mounted rotary casing having opposite sides and an encompassing ring or band presenting a uniform circular surface and from which power is to be transmitted, bearing members on which the opposite sides of said casing are mounted, a stationary eccentric shaft crossing said casing, a plurality of side-by-side rotary cylinder-assemblies mounted and independently rotatable on said shaft and each having a series of radially disposed cylinders and independent pistons slideable therein adapted at their outer ends to engage said circular surface of said band and rotate said casing, and inlet and exhaust ports for said cylinders, said inlet ports being arranged to admit the motive fluid to the cylinders as they travel along that portion of their movement when the arc prescribed by said cylinders and that prescribed by said casing are in near relation and gradually diverging.

7. A rotary motor of the type described comprising a concentrically mounted rotary casing having opposite sides and an encompassing ring or band presenting a uniform circular surface and from which power is to be transmitted, bearing members on which the opposite sides of said casing are mounted, a stationary eccentric shaft crossing said casing, a plurality of side-by-side rotary cylinder-assemblies mounted and rotatable on said shaft and each having a series of radially disposed cylinders and independent pistons slideable therein adapted at their outer ends to engage said circular surface of said band and rotate said casing, the cylinders of one assembly being high pressure cylinders and of the other assembly low pressure cylinders, an intake for motive fluid leading to said high pressure cylinders which may be traveling along those portions of their movement when the arc prescribed by said high pressure cylinders and that prescribed by said casing are in near relation and gradually diverging, an exhaust extending from said high pressure cylinders as said cylinders successively travel beyond the active zone for their respective pistons and leading to said low pressure cylinders which may be traveling along those portions of their movement when the arc prescribed by said low pressure cylinders and that prescribed by said casing are near together and gradually diverging, and an exhaust from said low pressure cylinders as said cylinders travel beyond the active zone for their pistons.

Signed at New York city, in the county of New York, and State of New York, this 9th day of June, A. D. 1920.

OTIS F. PRESBREY.
